UNITED STATES PATENT OFFICE.

CHARLES PERKES, OF PHILADELPHIA, PENNSYLVANIA.

DESIGN FOR A PISTON-HEAD.

SPECIFICATION forming part of Design No. 34,675, dated June 18, 1901.

Application filed May 15, 1901. Serial No. 60,411. Term of patent 14 years.

To all whom it may concern:

Be it known that I, CHARLES PERKES, a citizen of the United States, residing at Philadelphia, in the county of Philadelphia and State 5 of Pennsylvania, have invented and produced a new and original Design for Piston-Heads, of which the following is a specification, reference being had to the accompanying drawings, forming part thereof.

Figure 1 is a top plan view of my invention. Fig. 2 is a side elevation. Fig. 3 is a central vertical section. Fig. 4 is a bottom view.

1 represents the piston-head. 2 is the convex rounded upper portion of the same. 3 15 is an annular depression formed on the under side thereof.

4 is a threaded opening centrally through

the piston-head. 5 is an annular collar surrounding the lower end of said opening.

6 is an annular groove formed circumferentially of the piston-head upon its outer side. 20

7 represents a series of perforations connecting groove 6 with the annular recesses 3.

What I claim as new, and desire to secure by Letters Patent, is—

The design for a piston-head, substantially as shown and described.

In testimony whereof I have affixed my signature in the presence of two witnesses.

CHARLES PERKES.

Witnesses:

MILTON WOLF,
WM. A. SHRYOCK.
